UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TAKE-UP MECHANISM FOR NARROW WARE LOOMS.

Application filed October 20, 1920. Serial No. 418,133.

- This invention relates to takeup mechanism for narrow ware looms, particularly adapted for looms weaving relatively heavy fabric, such as canvas tape or brake linings.
- 5 It has been customary to build such looms with a single drive shaft for all of the takeup rolls. Thus constructed, it is necessary to stop the loom in order to independently adjust any particular takeup roll.
- 10 It is an important part of my invention to provide a construction in which any takeup roll may be independently and conveniently adjusted during the continued operation of the loom.
- 15 Another object is to provide a sectional drive for the takeup rolls, so that certain rolls may be driven at one speed and other rolls at a different speed or speeds, thus permitting the manufacture of two or more different weaves simultaneously.
- 20 With these general objects in view, my invention relates particularly to certain arrangements and combinations of parts which will be hereinafter described and more specifically set forth in the appended claims.
- A preferred form of my invention is shown in the drawings in which—
- Fig. 1 is a front elevation of a section of my improved takeup mechanism;
- 30 Figs. 2 and 3 are sectional side elevations, taken along the lines 2—2 and 3—3 of Fig. 1;
- Fig. 4 is an enlarged front elevation of the worm shaft shown in Fig. 3;
- Fig. 5 is a sectional plan view taken along the line 5—5 in Fig. 4, and
- 35 Fig. 6 is a diagrammatic front elevation of a portion of a narrow ware loom embodying my invention.
- Referring to Fig. 6, I have shown a portion of a narrow ware loom having a frame 10, a breast beam 11 and intermediate supports 12. A plurality of takeup rolls 13 are loosely mounted on drive shaft sections 14, 15 and 16. Each section of the shaft is supported in bearings at its opposite ends and is independently rotated by a ratchet feed indicated generally by the letter F. Each section is thus driven independently and may, if desired, be adjusted to suit the requirements of entirely different weaves. Provision is also made for independently adjusting any one of the takeup rolls 13 during the continued operation of the loom.
- 40 I will now more particularly describe the construction and operation of a single section of my improved takeup mechanism. Each section of the drive shaft, as 14, is provided with a ratchet wheel 17 fixed to the shaft and intermittently advanced by a pawl 18 mounted on a feed lever 19 pivoted on the shaft 14 and actuated by a link 20 adjustably connected thereto. The link 20 is regularly reciprocated from the crank shaft of the loom or in any other convenient manner.
- 45 An internal gear 21 for each takeup roll is loosely mounted on the shaft 14 and is provided with worm gear teeth 22 on its outer surface, engaged by a worm 23 fixed on a short shaft 24 rotatable in a bearing 25 above the internal gear 21. The worm 23 has a plurality of notches 26, (Fig. 4) formed in the hub thereof, adapted to receive a projection 27 (Fig. 5) on a latch 28. The latch is pivoted at 29 to the bearing 25 and is provided with a spring 30 by which it is held in yielding engagement with one of the notches 26.
- 50 The outer end of the shaft 24 is squared to receive a wrench 31. The end of the wrench may be beveled as shown at 32, so that it will engage the inwardly projecting portion 33 of the latch 28, pressing the same outwardly and releasing the worm as the wrench is placed in position to turn the shaft 24.
- The gear 34 (Fig. 1) is mounted on a stud 35 fixed in a lug 36 projecting from the side of the takeup roll 13. The gear 34 meshes with pinion teeth 37 which may be cut directly in the shaft 14. A second gear 38 is fixed to the gear 34 and engages the teeth of the internal gear 21. As the shaft 14 is rotated, the takeup roll 13 is thus advanced slowly with a planetary drive.
- 55 The mechanism is usually so constructed that two or more takeup rolls will be driven by each section of the drive shaft. The rolls driven by a single section will thus be advanced at uniform speed but any separate roll may be independently advanced by turning the worm associated therewith. The usual top roll 40 is provided to operate with each takeup roll 13. If desired, a separate ratchet drive for each roll may of course be used.
- 60 Having thus described my invention, it

will be seen that each section may be driven at any desired rate by adjusting the corresponding link 20 in the slotted arm of its lever 19, and that each roll 13 may be independently advanced or retarded by the use of the worm 23 associated therewith, which latter adjustment may be made without interfering with the continued operation of the loom. All parts of the mechanism are strongly built and are well adapted for the weaving of heavy fabrics.

It will also be evident that changes and modifications may be made therein by those skilled in the art within the spirit and scope of my invention as set forth in the claims, and I do not wish to be otherwise limited to the details herein disclosed, but what I do claim is:—

1. A takeup mechanism for a narrow ware loom, comprising a takeup roll, a roll shaft, means to rotate said shaft, a planetary gear connection between said roll and said shaft including a normally stationary internal gear, and manual means to angularly adjust said internal gear in either direction to any desired extent.

2. A takeup mechanism for a narrow ware loom, comprising a takeup roll, a roll shaft, means to rotate said shaft, a planetary gear connection between said roll and

said shaft including a normally stationary internal gear, worm gear teeth fixed in relation to said internal gear, and a manually movable worm meshing with said worm gear teeth for adjustment thereof.

3. A takeup mechanism for a narrow ware loom, comprising a takeup roll, a roll shaft, means to rotate said shaft, a planetary gear connection between said roll and said shaft including a normally stationary internal gear, worm gear teeth fixed in relation to said internal gear, a manually movable worm meshing with said worm gear teeth for adjustment thereof, and means to lock said worm.

4. A takeup mechanism for a narrow ware loom, comprising a takeup roll, a roll shaft, means to rotate said shaft, a planetary gear connection between said roll and said shaft including a normally stationary internal gear, worm gear teeth fixed in relation to said internal gear, a worm meshing therewith, a detachable wrench for turning said worm, and a latch for said worm, said latch being released by attachment of said wrench to said shaft.

In testimony whereof I have hereunto affixed my signature.

ELBRIDGE R. HOLMES.
